UNITED STATES PATENT OFFICE

2,385,239

DIESEL ENGINE FUEL INJECTOR

Samuel A. Unsworth, Lawrenceville, Ill.

Application February 8, 1943, Serial No. 475,152

1 Claim. (Cl. 123—139)

The present invention relates to new and useful improvements in fuel injecting means for Diesel engines, and has for its primary object to provide, in a manner as hereinafter set forth, a combined pump and injector unit of novel construction which is devoid of the usual gears, push rods, et cetera, and which is adapted to be installed on the cylinder head of the engine for operation by compression from the cylinder.

Another very important object of the invention is to provide a combination fuel injector and pump unit of the aforementioned character which embodies unique control means.

Other objects of the invention are to provide a Diesel engine fuel injector and pump combination of the character described which will be comparatively simple in construction, strong, durable, highly efficient and reliable in use, compact, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of the device.

Figure 2 is a vertical sectional view, taken substantially on the line 2—2 of Figure 1.

Figure 3 is a view in horizontal section, taken substantially on the line 3—3 of Figure 2.

Figure 4 is a view in horizontal section, taken substantially on the line 4—4 of Figure 2.

Figure 5 is a fragmentary view in vertical section through an intermediate portion of the device.

Figure 6 is a detail view in elevation of the fuel compressing piston.

Figure 7 is a detail view in elevation of the lower cylinder.

Figure 8 is a top plan view of the lower cylinder.

Referring now to the drawings in detail, it will be seen that the embodiment of the invention which has been illustrated comprises a cylinder 1 which is mounted in the head 2 of the engine cylinder 3 in communication with the combustion chamber thereof. A seat 4 is provided in the upper portion of the bore of the cylinder 1. The upper portion of the cylinder 1 is also formed to provide an external seat 5.

A vertically elongated cast body 6 is mounted on the seat 5. The body 6 comprises an out-turned flange 7 on its lower end which is aper-

tured for the passage of bolts 8 for securing the assembly in position on the head 2.

The body 6 has formed therein upper and lower cylinders 9 and 10, respectively, which are separated by a horizontal partition 11. A piston 12 is mounted for reciprocation in the cylinder 10. Rising from the piston 12 is a rod 13 which passes slidably through a stuffing box 14 in the partition 11 into the upper cylinder 9. A piston 15 on the upper end portion of the rod 13 is operable in the cylinder 9. A removable screw plug 16 closes the cylinder 9 at its upper end. A coil spring 17 is mounted under tension between the plug 16 and the piston 15.

Extending upwardly in the piston 12 from the lower end thereof is a bore 18. Ports 19 in the upper portion of the piston 12 establish communication between the bore 18 and the fuel compression chamber in the upper portion of the cylinder 10. A piston 20 is operable in the cylinder 1 and engageable with the seat 4. The piston 20 is provided with a tubular rod 21 which is threaded into the lower portion of the bore 18 of the piston 12, said tubular rod passing through an opening 22 which is provided therefor in the upper portion of the cylinder 1. It will thus be seen that the pistons 20, 12 and 15 are rigidly connected for operation in unison. The bore of the tubular rod 21 extends downwardly through the piston 20 and is enlarged to provide a seat 23.

A valve 24 in the piston 20 is engageable with the seat 23 for closing the tubular rod 21. The valve 24 is provided with ports or passages 25 which, when said valve is closed, are closed by the seat 23. The valve 24 further includes a stem 26 which extends upwardly through the bore of the tubular rod 21 into the bore 18 in the piston 12. A coil spring 27 is operatively connected to the upper end of the stem 26 for closing the valve 24.

An annular cushion 28 is provided on the top of the cylinder 1 for the piston 12. The piston 15 has formed therein a passage 29 which is controlled by an upwardly opening, spring-seated check valve 30. A bypass 31 establishes communication between the upper and lower portions of the cylinder 9 around the piston 15. A port 32 communicates with the cylinder 9 at a point between the ends of the bypass 31. A pipe 33 communicates with the port 32 at one end. At its other end, the pipe 33 communicates with a port 34 in the upper portion of the engine cylinder 3. The port 34 is controlled by the engine piston 35 in the cylinder 3. The engine piston 35 has formed therein

45 which is controlled by an upwardly opening, spring-seated check valve 36. A bypass 37 establishes communication between the upper and lower portions of the cylinder 9 around the piston 15. A port 38 communicates with the cylinder 9 at a point between the ends of the bypass 37. A pipe 39 communicates with the port 38 at one end. At its other end, the pipe 39 communicates with a port 40 in the upper portion of the engine cylinder 3. The port 40 is controlled by the engine piston 41 in the cylinder 3. The engine piston 41 has formed therein

a port or passage 36 for communication with the port 34.

The body 6 is formed to provide a chamber 37 to which a fuel line 38 is connected. The fuel chamber 37 communicates with the cylinder 10, at an intermediate point, through a vertical series of ports 39. The body 6 has formed therein a vertical bore 40, the lower portion of which intersects the ports 39. Operable in the bore 40 is a gate valve 41 in the form of a rod which controls the ports 39. A bell crank lever 42 is pivotally mounted on a suitable support 43 on the upper end of the body 6. A control rod 44 is pivotally connected to one end portion of the lever 42. The other end of the lever 42 is operatively connected by links 45 to the fuel control valve 41.

The fuel chamber 37 also communicates with the cylinder 10, at a point above the ports 39, through an angular intake passage 46. A suction-opened, spring-seated check valve 47 controls the fuel intake passage 46. The passage 46 is further provided with a bleeder valve 48.

Briefly, the operation of the device is substantially as follows:

With the control valve 41 in lowered or closed position, fuel is drawn from the chamber 37 through the intake passage 46 past the valve 47 into the upper portion of the cylinder 10 by the piston 12 when said piston 12 and the pistons 15 and 20 move downwardly. With the pistons 15, 12 and 20 in lowered position, the engine piston 35 moves upwardly on its compression stroke in the engine cylinder 3. In this manner a balanced pressure is created beneath the piston 20, and above the piston 15 through the port 34, the pipe 33 and the port 32. This balanced pressure is built up until the engine piston 35 closes the port 34. The engine piston 35 continues to move upwardly and the pressure is increased beneath the piston 20. When the port 36 communicates with the port 34, the pressure in the cylinder 9 above the piston 15 is released. This sudden unbalancing of the pressure above and below the assembly causes the pistons 20, 15 and 12 to move upwardly in their respective cylinders, the latter compressing the fuel in the upper portion of its cylinder 10. This compressed fuel rushes through the ports 19 into the bore 18 and opens the valve 24 against the tension of the spring 27. When the valve 24 is thus opened, the fuel passes through the ports 25 into the firing chamber of the engine cylinder 3. This injection operation ceases when the piston 20 engages the seat 4 and is arrested thereby. The assembly is held in raised position during the firing stroke of the engine by the pressure in the cylinder 3. The piston 15, when in raised position, as seen in Figure 2 of the drawings, closes the port 32 for preventing pressure from entering the cylinder 9 during the power stroke of the engine. The bypass 31 prevents air or gas from being trapped in the cylinder 9 above and below the piston 15 and also prevents the creation of a vacuum in said cylinder. When the piston 15 is in lowered position, it closes the bypass 31 at its lower end. The check valve 30 prevents the trapping of air or gas below the

piston 15 when the bypass 31 is thus closed. Of course, the coil spring 17 yieldingly urges the assembly downwardly. When the fuel injection operation ceases, the valve 24 is closed by its spring 27. The lowermost port 39 is just above the piston 12 when it is down, and the uppermost port 39 is just above said piston when it is up. When the piston 12 moves upwardly on its compression stroke and with the control valve 41 in fully closed position, all of the ports 39 are closed and none of the fuel which has been previously drawn into the upper portion of the cylinder 10 through the passage 6 can escape back to the chamber 37 through said ports. Thus, the maximum fuel charge will be compressed in the upper portion of the cylinder 10. When the control valve 41 is raised, the ports 39, beginning with the lowermost thereof, are successively opened for permitting the desired portion of the fuel in the cylinder 10 to return to the chamber 37 when the piston 12 moves upwardly. In this manner the volume of fuel injected into the engine cylinder may be controlled or regulated as desired. With the control valve 41 in fully open position, all of the ports 39 will be open and consequently substantially all of the fuel in the cylinder 10 will be returned to the chamber 37.

It is believed that the many advantages of a fuel injecting means constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

In combination with a Diesel engine comprising a cylinder having a port therein near the top thereof and a piston operable in the cylinder and controlling the port, said piston having a vent port therein near the top thereof for communication with the first-named port, upper, lower and intermediate cylinders mounted on the engine, said lower cylinder communicating with the top of the engine cylinder for receiving pressure therefrom, pistons operable in the upper, lower and intermediate cylinders, the second-named pistons being connected for operation in unison, the piston in the lower cylinder being operable by pressure from the engine cylinder, a conduit connecting the first-named port to the upper cylinder for conducting pressure thereto above the piston therein when the latter is lowered, the latter piston, when raised, acting to cut off communication of its cylinder with said conduit, the piston in the intermediate cylinder constituting means for drawing fuel thereinto and compressing said fuel, means to prevent creation of a partial vacuum and pressure, respectively, on opposite sides of the piston in the upper cylinder when said piston is moved, and valve controlled means for conducting the compressed fuel into the engine cylinder.

SAMUEL A. UNSWORTH.
